P. A. GEIER.
DUST RECEPTACLE FOR VACUUM CLEANING APPARATUS.
APPLICATION FILED JULY 19, 1916.

Attorney.

UNITED STATES PATENT OFFICE.

PHILIP A. GEIER, OF CLEVELAND, OHIO, ASSIGNOR TO THE P. A. GEIER COMPANY, OF CLEVELAND, OHIO, A CORPORATION OF OHIO.

DUST-RECEPTACLE FOR VACUUM CLEANING APPARATUS.

1,383,615.

Specification of Letters Patent.

Patented July 5, 1921.

Application filed July 19, 1916. Serial No. 110,222.

To all whom it may concern:

Be it known that PHILIP A. GEIER, a citizen of the United States, residing at Cleveland, in the county of Cuyahoga and 5 State of Ohio, has invented certain new and useful Improvements in Dust- Receptacles for Vacuum Cleaning Apparatus, of which the following is a specification.

My invention relates to improvements in 10 dust receptacles for vacuum cleaning apparatus, and has for its object the production of a receptacle for temporarily holding refuse collected by a vacuum cleaner.

In a device of this character the receptacle 15 is made from suitable fabric which permits the air to pass with relative freedom while retaining the dust, lint and foreign material within the bag until such time as it is desired to empty it. It is important, however, 20 that the refuse shall not be permitted to return to the fan or other vacuum producer, and that the collected dust and refuse shall remain as nearly undisturbed as possible, until the contents of the bag have been 25 emptied. Moreover, it is important that the flow of air shall be relatively as unimpeded as possible. On this account certain forms of valves which have been used hitherto, present the objection that they become 30 filled rearwardly with the accumulated refuse, and thereby restrict the flow of air while causing a constant disturbance of the collected material, whereby the finer portions of the dust are caused to be driven 35 through the fabric.

My invention contemplates the provision in a fabric receptacle of this class, of a partial diaphragm or partition placed near the entrance to the bag while affording a 40 passageway above said partition of such unobstructed area as will accommodate the dust-laden air at all times. Said diaphragm affords a retaining wall within the bag which prevents the return of the accumulated 45 refuse, and at the same time directs the air currents above such refuse, so that it remains relatively undisturbed within the bag or receptacle.

The structural features of my invention 50 may best be explained and understood by making reference to the accompanying drawings, wherein:—

Figure 1 is a view in side elevation, partially broken away, of a dust receptacle constructed in accordance with my invention.

Fig. 2 is a cross-sectional view on line 2—2, Fig. 1. Fig. 3 is a fragmentary plan view. Fig. 4 is another fragmentary view illustrating the closure means for the open end or top of the bag, and Fig. 5 is a view in side 60 elevation, partially broken away, of a vacuum cleaner and associated dust receptacle.

Throughout the several figures of the drawings, I have employed the same character of reference to indicate similar parts. 65

Referring to Fig. 1, it is seen that the dust receptacle *a*, which is suitably constructed of fabric, has an entrance mouth *a'* adapted to fit closely upon the exhaust part or nozzle *b* of a portable vacuum cleaner, such for example, as is shown in Fig. 5. The latter device, as is well known in the art, usually provides a fan for drawing the dirt and refuse through an inlet nozzle *c*, and directing it through the outlet nozzle *b* into the 70 fabric dust receptacle. Positioned before said nozzle within the dust receptacle *a*, is a partial diaphragm or partition *d* which may well be a fabric member stitched to the bottom and sides of said receptacle; 75 leaving, however, a space *e* between the upper wall of the receptacle and said diaphragm, of an area equal to or greater than that of the exhaust nozzle.

In Fig. 1 I have shown by dotted lines, 85 approximately the maximum accumulation of dust, dirt and other refuse within the receptacle, which in a portable cleaner ordinarily is supported at an angle of about 45° in alignment with and by the handle *f* of 90 the vacuum cleaner. This is accomplished by a loop or chain *f'*, which is attached to a clip *g*, adapted to be slipped over the open end of the fabric receptacle for holding the same tightly closed until such time as the 95 contents of the receptacle are to be emptied.

The arrows shown in Fig. 1 are intended to indicate generally, the course of the dust-laden air currents which are directed over the upper edge of the diaphragm and into 100 the free portion of the fabric receptacle *a*. From this the air escapes through the fabric walls, while the dust, dirt and other refuse fall and accumulate behind the partial diaphragm *d*, which prevents the return of this 105 foreign material to the fan or pump chamber.

Preferably the receptacle is offset laterally as shown in Fig. 3, in order to bring it 110 symmetrically beneath the supporting han-

dle of the vacuum cleaner, and also, the bottom of the bag is pouched as shown in Fig. 1 to afford a more spacious container for the refuse.

5 These, with other features explained, are details of construction, which are not essential to my invention, except as defined in and by the accompanying claims.

10 Having now set forth the preferred embodiment of my invention, I claim as new and desire to secure by Letters Patent, the following:—

15 1. In a device of the class described, the combination with a fabric-walled receptacle, having an inlet opening, of a partial diaphragm positioned therein adjacent to said opening and partitioning the lower portion of the receptacle from side to side, but af-

fording a passage in the upper portion of said receptacle above the diaphragm approximately of the size of the inlet opening, substantially as set forth. 20

2. In a device of the class described, the combination with a fabric-walled receptacle having an inlet and an outlet opening, of a partial diaphragm intermediate of said openings partitioning the lower portion of said receptacle from side to side, substantially as set forth. 25

In testimony whereof I do now affix my 30 signature in the presence of two witnesses.

PHILIP A. GEIER.
